UNITED STATES PATENT OFFICE.

ALBERT M. BURRITT, OF WATERBURY, CONNECTICUT, ASSIGNOR TO THE
A. BURRITT HARDWARE COMPANY, OF SAME PLACE.

FIRE-EXTINGUISHER.

SPECIFICATION forming part of Letters Patent No. 243,206, dated June 21, 1881.

Application filed April 16, 1881. (No model.)

To all whom it may concern:

Be it known that I, ALBERT M. BURRITT, of Waterbury, in the county of New Haven and State of Connecticut, have invented a new Improvement in Fire-Extinguishers; and I do hereby declare the following, when taken in connection with the accompanying drawings, and the letters of reference marked thereon, to be a full, clear, and exact description of the same, and which said drawings constitute part of this specification, and represent, in—

Figure 1, side view; Fig. 2, longitudinal central section.

This invention relates to an improvement in fire-extinguishers, with special reference to that class which are constructed to let on a flow of water by the influence of heat generated by the fire on the device which stops the flow of water, and so that the water will be thrown through the perforations in the distributor in the form of spray, such distributor being commonly called a "rose."

In order to protect the distributor from the lodgment of dust or other foreign particles therein which might obstruct the flow of water, a cap is arranged as a cover for the rose. In some cases this is soldered at the edge around the rose as a stop for the water, so that when the heat is sufficient to fuse the connection it will be thrown off and permit the flow of the water. In other cases there is a plug in the water-way back of the distributor. The cap is simply set loosely over the distributor, so as to be easily thrown off when the flow of water comes to it. It is on this latter arrangement that my invention is an improvement—that is to say, in the class of caps which are not for the purpose of stopping the flow of the water.

The use of the free cap serves a very good purpose where the distributors are set perpendicular—that is, so as to throw upward; but in many cases it is desirable and necessary that the rose should be turned downward. In that case the loose cap cannot be employed, and in any case the loose cap is liable to be accidentally removed.

The object of this invention is to secure the cap over the distributor in such a manner that the force of the water alone will disconnect it, and yet so that it is not liable to accidental disconnection; and in such construction my invention consists.

A represents the perforated rose or distributor; B, a thin metal cap fitted and set on over the rose and inclosing it, as shown in Fig. 2. At the center or closed end of the cap a small perforation, as at a, is made, exposing a point of the rose beneath. Through this perforation a drop of solder, b, is introduced, which so far connects the cap to the rose that the cap will be retained in this position, but yet when the flow of water is let on the pressure on the large interior surface of the cap will be sufficient to throw the cap from the rose, the force being greater than the strength of the connection.

Instead of a drop of solder, as proposed, the rose may be made with a stud projecting from it to pass through the perforation in the cap, and slightly headed upon the outside, just sufficient to retain the cap. I prefer, however, a soft-metal connection, the essential feature being that the cap shall be connected to the rose by a connection which readily yields when the pressure of the water is brought upon the inside of the cap.

From the foregoing it will be understood that I do not broadly claim a cover for the rose or distributor in a fire-extinguisher; but

What I do claim is—

A rose-distributor combined with a cap attached thereto by a contrivance substantially such as described, and so as to permit the disconnection of the cap when the pressure of water comes upon the inside of the cap, substantially as described.

ALBERT M. BURRITT.
